(57) **CLAIM**

The ornamental design for an electronic surveillance tag for clothing, textiles, fabric articles and the like, as shown and described.

DESCRIPTION

FIG. 1 is a front perspective view of an electronic surveillance tag for clothing, textiles, fabric articles and the like showing our new design;

FIG. 2 is a back perspective view thereof;

FIG. 3 is a front view thereof;

FIG. 4 is a back view of the electronic surveillance tag for clothing, textiles, fabric articles and the like, as inverted;

FIG. 5 is a right side view thereof;

FIG. 6 is a top view thereof; and,

FIG. 7 is a bottom view thereof.

The broken lines in the figures depict portions of the electronic surveillance tag for clothing, textiles, fabric articles and the like that form no part of the claimed design.

1 Claim, 5 Drawing Sheets
